UNITED STATES PATENT OFFICE.

NICHOLAS J. DOYLE, OF BUFFALO, NEW YORK.

APPARATUS FOR HOLDING AND DISCHARGING COINS.

Application filed November 1, 1921. Serial No. 512,093.

To all whom it may concern:

Be it known that I, NICHOLAS J. DOYLE, a citizen of the United States of America, and a resident of the city of Buffalo, county 5 of Erie, and State of New York, have invented certain new and useful Improvements in Apparatus for Holding and Discharging Coins, of which the following is a full, clear, and exact description.

10 My device relates generally to an apparatus for holding and discharging coins, and particularly to a device of this nature which may be made a part of a woman's hand bag or a man's coat pocket.

15 The principal object of my invention has been to provide a device of this nature which shall be compact in design, simple and easy to operate, and cheap to manufacture.

Another object has been to provide such a 20 device with means, whereby the accidental discharge of coins may be prevented.

Another object has been to provide the device with chutes so accurately sized that mutilated coins cannot be inserted therein.

25 Furthermore, my device is provided with locking means at the upper end of each of the chutes, whereby the coins contained in the chutes cannot be accidentally spilled out.

The above objects and advantages have 30 been accomplished by the device shown in the accompanying drawings, of which:

Fig. 1 is a side elevation, partly in section, of my device as applied to a woman's hand bag.

35 Fig. 2 is a vertical, sectional view thereof and is taken on line 2—2 of Fig. 1.

Fig. 3 is a vertical, sectional view showing the device as applied to a man's coat pocket.

Referring more particularly to the form 40 shown in Figs. 1 and 2, 5 represents a woman's hand bag, the front portion 6 thereof being removed in Fig. 1.

The device comprises a coin block 7 which is provided with a plurality of vertically arranged coin chutes 8, 9 and 10, of a number 45 equal to the number of different denominations of coins which it is desired to handle with the device, and each a size accurately fitting the size of coin for which it is intended.

Pivottally arranged near the bottom of the block 7 and opposite each of the chutes 8, 9 and 10, is a discharge plate 11. Each of these discharge plates is provided with two 50 lower prongs 12 and two upper prongs 13. Apertures 14 are provided in the face of the

coin block 7 for the passage of the prongs 12 and similar apertures 15 are provided for the passage of the prongs 13. The apertures and prongs are so proportioned and 60 positioned that the upper prongs 13 will retain the second coin in any of the chutes before the lower prongs 12 have released the first coin. A spring 16 is provided for each of the discharge plates 11, and is preferably 65 arranged about the pivotal pin 17 of each plate, whereby the plate will always be maintained in the position shown in Fig. 2, except when it is operated to discharge a coin. Each of the discharge plates is provided 70 with an operating button 18, which projects outwardly sufficiently far to pass through the front portion 6 of the hand bag and be conveniently operated. A guard 19 preferably extends across the coin block 7 and 75 protects the discharge plates 11 from being damaged. Each discharge plate is provided with a downwardly extending tab 20, which contacts with the face of the coin block 7, and serves to limit the movement of the dis- 80 charge plate.

Locking means are provided for preventing the discharge plates from being accidentally operated by pressure applied to them. These means comprise a lock bar 21 which 85 is slidably mounted upon the face of the coin block 7 and arranged opposite the upper ends of the discharge plates 11. The lock bar is preferably held in position by means of screws 22 which engage with slots 23 90 formed therein. The central portion of the lock bar is provided with a semi-circular recess 24, with which the lower end 25 of a lock arm 26 is engageable. The lock arm is pivoted at 27, and provides means for shifting the lock bar from its locked position to its unlocked position, or vice versa. Two conical lugs 28 and 29 are provided on the face of the coin block 7 and so arranged as to engage with an aperture 30, formed 100 through an operating knob 31 when the lock arm 26 is in either of its extreme positions. The lock bar 21 is provided with a plurality of outwardly extending lugs 32, equal in number to the number of chutes employed. 105 When the lock bar is in its locking position, or a position opposite to that shown in Fig. 1, each of these lugs 32 will engage with an upwardly extending tab 33, formed on each of the discharge plates 11 and thus serve to 110 prevent the discharge plates from being operated. The lock arm 26 is preferably

made of a resilient material, and is therefore in springing engagement with either of the lugs 28 or 29, so that the lock bar will not become accidentally disengaged.

5 The upper end of each of the chutes 8, 9 and 10 is provided with coin retaining means, each comprising a spring 34 secured at its lower end to the back of the coin block 7. The upper end of the spring is provided with a right angled bent portion 35, which enters a slot 36 formed in the block. The upper edge of the end portion 35 is tapered or curved as shown in the drawings, so that it will be moved backwardly and 15 out of the way when the coin is inserted. The lower edge, however, is arranged at right angles to the chute, so that coins will be prevented from passing out of this end of the chute. The hand bag is, of course, provided with openings 39 through which coins may be passed to the coin chutes and also with openings 46 through which the coins may be discharged as they come from the chutes. The guard 19 and portion 6 of the 20 purse are also provided with apertures 37 and 38, respectively, through which the stems of the operating buttons 18 are passed. The coin block 7 may be cut away along its upper edge opposite the upper end of each of the chutes (see Fig. 1), so as to facilitate the insertion of the coins into the chutes.

Referring now to Fig. 3, where I show the device used in connection with a coat pocket, 40 is the outer material of the coat and 41 the lining thereof, 42 and 43 represent, respectively, the outer and inner folds of the pocket of the coat. The device is attached preferably to the inner fold 43 of the pocket by means of the screws 44. The operating buttons 18, and the lock bar operating knob 31 are passed through suitable apertures formed in the inner fold 43 of the lining and project into the pocket.

When the device is loaded, the coins are 45 passed one at a time into their respective chutes and the lowermost one will fall to the bottom of the chute and engage with the lower tabs 12 of each of the discharge plates. As each coin is passed into the chute, the right angled portion 35 of the retaining means will be forced backwardly until the coin has passed, when it will be sprung inwardly and occupy the position shown in Fig. 2, thereby retaining the coins in the chutes even though the device is turned up-side-down. When the lock bar 21 and the lock arm 26 are in the positions shown in Fig. 1, the discharge plates may be operated. When it is desired to discharge a coin, the operating button 18 50 of the discharge plate controlling the chute having the desired coin is pressed inwardly, whereupon the upper tabs 13 will engage with the second coin, immediately after which the lower tabs 12 will release the lowermost coin 60 and drop it from the chute. When pushing 65

the operating buttons 18, the hand of the operator is placed beneath the purse or pocket so that the coin may be deposited in the hand. Each time the discharge plate is operated another coin will be dropped until 70 all of the coins in the chute selected will have been discharged. After the desired number of coins have been discharged from the device, the lock arm 26 is moved so that its operating knob engages with the lug 29, whereupon the lock bar 21 will be moved to a position opposite to that shown in Fig. 1, which will bring the tabs 32 carried by the lock bar in registering positions with the tabs 33 of the discharge plates. When in these 80 positions, the discharge plates will be prevented from being operated accidentally or otherwise.

While I have shown my device as applied to a woman's hand bag and the pocket of a coat, it is obvious that it may be used anywhere that it is desired to hold and deliver coins. Furthermore, while I have shown the coin block of a solid piece of material, it may be made of a number of pieces of material. These and other modifications of the details herein shown and described may be made without departing from the spirit of my invention or the scope of the appended claims; and I do not, therefore, wish to be limited to the exact embodiment herein shown and described, the form described being merely a preferred embodiment thereof.

Having thus described my invention, what I claim is:

1. An apparatus for holding and discharging coins comprising a coin chute, having two pairs of openings in one of its faces, a one-piece discharge plate having two pairs of inwardly extending tabs, alternately passing 105 through the registering openings, an upwardly extending tab carried by the discharge plate, and means engageable with the upwardly extending tab for locking the discharge plate in its inoperative position.

2. An apparatus for holding and discharging coins comprising a coin chute, having two pairs of openings in one of its faces, a one-piece discharge plate having two pairs of inwardly extending tabs, alternately passing 115 through the registering openings, an upwardly extending tab carried by the discharge plate, a reciprocating lock bar having a tab engageable with the upwardly extending tab of the discharge plate for locking the discharge plate in its inoperative position, and means for controlling the movement of the lock bar.

3. An apparatus for holding and discharging coins comprising a coin chute having 125 two pairs of openings in one of its faces, a discharge plate having two pairs of inwardly extending tabs, alternately passing through the registering openings, a stop tab carried by the discharge plate for limiting 130

its motion in one direction, an upwardly extending tab, and means engageable with the upwardly extending tab for limiting the motion of the discharge plate in the opposite direction.

4. An apparatus for holding and discharging coins comprising a coin chute having two pairs of openings in one of its faces, a discharge plate having two pairs of inwardly extending tabs, alternately passing through 10 the registering openings, a stop tab carried

by the discharge plate for limiting its motion in one direction, an upwardly extending tab, a reciprocating lock bar having a tab engageable with the upwardly extending tab of the discharge plate for limiting the movement of the discharge plate in the opposite direction, and means for controlling the movement of the lock bar.

In testimony whereof, I have hereunto signed my name.

NICHOLAS J. DOYLE.
